UNITED STATES PATENT OFFICE.

WILLIAM GORMAN, OF NEW BRITAIN, CONNECTICUT, ASSIGNOR TO THE
RUSSELL & ERWIN MANUFACTURING COMPANY, OF SAME PLACE.

DESIGN FOR LOCK ESCUTCHEON-PLATE.

Specification forming part of Design No. 6,867, dated September 2, 1873; application filed August 11, 1873.
[Term of Patent 14 years.]

To all whom it may concern:

Be it known that I, WILLIAM GORMAN, of New Britain, in the county of Hartford and State of Connecticut, have invented a new Design for a Lock Escutcheon-Plate; and I do hereby declare that the following specification, taken in connection with the drawing, is a full, clear, and exact description thereof.

The general form of the plate is that of an armorial shield. Around the outer edge, except at the salient angles, where scroll-supporters *a* are placed, is a band line or lines, *b*, which, at the top of the plate, meet the central trefoil key *c*. The band lines *b* are also returned around the two upper screw-holes in the plate. The key-hole is surrounded by an ornamental band, *d*, of oval form, and the

space between this and the band lines *b* is filled with ornamental scroll-work in relief.

The characteristic feature of my new design is not the ornamental scroll-work between the oval band *d* and the edge band *b*, for this may be omitted altogether; but it is the distinctive effect to the eye which results from the central oval band *d* surrounding the key-hole, and the edge band *b*, around the edge of the shield.

What I claim as new, and desire to secure by Letters Patent, is—

The design for a lock escutcheon-plate, substantially as described, and shown in the drawing.

Witnesses: WILLIAM GORMAN.

M. J. WOODRUFF,

THEO. E. SMITH.
